(57) **CLAIM**

The ornamental design for a dumbbell stand, as shown and described.

DESCRIPTION

FIG. 1 is a front, right, top perspective view of a dumbbell stand, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view of the enlarged scale thereof;

FIG. 8 is a bottom plan view of the enlarged scale thereof;

FIG. 9 is an enlarged view of detail 9 in FIG. 1;

FIG. 10 is an enlarged view of detail 10 in FIG. 1;

FIG. 11 is an enlarged view of detail 11 in FIG. 5; and,

FIG. 12 is an enlarged view of detail 12 in FIG. 7.

The dashed broken lines in the figures illustrate portions of the dumbbell stand that form no part of the claimed design. The dash-dot-dash broken lines are for notating enlarged views and form no part of the claimed design.
